AUTOMOBILE

Bruce B. Mohs, Rte. 1, Waunakee, Wis. 53597

Filed July 9, 1968, Ser. No. 12,661

Term of patent 14 years

Int. Cl. D12—08

U.S. Cl. D14—3

FIG. 1

FIG. 2

I claim:

The ornamental design for an automobile, as shown and described.
